UNITED STATES PATENT OFFICE

PAUL C. RAWLS, OF DES MOINES, IOWA, ASSIGNOR TO TECHNICAL EQUIPMENT COMPANY, OF DES MOINES, IOWA, A CORPORATION OF IOWA

HIGH FREQUENCY OSCILLATORY CIRCUIT FOR THERAPEUTIC PURPOSES

Application filed November 3, 1930. Serial No. 493,024.

The object of my invention is to provide an improved high frequency oscillatory circuit particularly adapted to produce extremely high frequency oscillating current for therapeutic purposes, and in which is employed the ordinary two electrode vacuum tube for producing the necessary high frequency oscillating current, and voltage variations.

Heretofore a considerable difficulty has 10 been experienced in the application of therapeutics employing high frequency oscillating currents of appreciable amount, due to the fact that it has been impossible to maintain a constant predetermined frequency of 15 oscillation during the entire time of a single application or operation, and at the same time be able to vary the amount of current as applied to the treatment through a comparatively large range of time to meet the 20 requirements of the treatment being given. Therefore, the art of therapeutics has not advanced as might be expected, as the success of the method of treatment depends largely on being able to easily and positively control the amount of current and the frequency 25 of its oscillation.

Especially in view of the limitations of the existing oscillators employing a spark gap, which apparatus is very unreliable in its 30 operation, it is almost impossible to maintain a constant frequency during the time of a treatment and at the same time vary the amount of current, as any variation of the amount of current results in variation of the frequency 35 of this type of oscillator.

It is, therefore, the object of my invention to provide an improved high frequency oscillating circuit for therapeutic purposes in which a predetermined frequency of the current oscillation may be positively and easily 40 maintained, for any desired time, and at the same time permitting a comparatively large amount of current variation as applied to the point of application.

45 A further object is to provide in an oscilla-

tory circuit for therapeutic purposes, and in which is included an electrically operating knife, improved means in connection with the knife whereby the amount of current may be controlled by the operator's thumb, 50 so that the operator may always have at his command any desired amount of current.

My invention consists in the construction, arrangement and combination of the various parts of the device, whereby the objects contemplated are attained, as hereinafter more fully set forth, pointed out in my claims, and illustrated in the accompanying drawing, in which:

Figure 1 is a diagram of my improved oscillatory circuit.

Figure 2 is a detail sectional view of one form of knife used in connection therewith.

My improved oscillatory circuit comprises a pair of vacuum tubes 10 of the type employing a heating filament, a plate and a grid. The filaments 11 of the tubes are mounted in parallel relation. The negative ends of the filaments are connected by a conductor 12 and the positive ends of the filament 13 are connected by a conductor 14. A battery 15 or other suitable current supply is provided for heating the filaments. One side of the battery is connected to the conductor 13 by a conductor 15, and the opposite side of the conductor 12 by a conductor 16. A voltage meter 17 is connected between the conductors 15 and 16. Plates 18 of the tubes are connected to conductors 19 connected to the opposite ends of an inductance coil 20, having a center tap 21 connected to a conductor 22 forming a part of the plate circuit, in which is included a battery 23 or other suitable means for supplying the plate current. The conductor 22 also includes a milliampere 85 meter 24.

The grids 25 of the tubes 10 are connected to conductors 26, which in turn are connected to the opposite ends of the inductance coil 27, which is provided with a center tap 28 90

having a conductor 29 making a neutral connection with the negative conductor 12.

Inductively connected to the plate coil 20 is an output coil 30, one end of which is connected to a conductor 31 in which is included 5 a variable condenser 32. The free end of the conductor 31 is connected to the blade of a knife 33. The opposite end of the inductance coil 30 is provided with a conductor 34 in which is included a milliamperes meter 35, and has its free end provided with a wrist clamp 36. The conductors 31 and 34 and the inductance coil 30 constitute what I shall term the output circuit.

10 Inductively connected to the central portion of the grid coil 27 is a coil 37 of very few turns of wire. One end of the coil 37 is provided with a conductor 38 and the opposite end of the coil with a conductor 39. The free ends of the conductors are connected to a 15 variable non-inductive resistance 40. This resistance is preferably of the carbon disc type which is mounted in the handle 41 of the knife 33. The handle of said knife is provided with a slot 42 in which is mounted 20 an arm 43 having its inner end supported against a conductor disc 44 and its opposite end pivotally connected to a suitable bracket 25 45 projecting outwardly from the handle 41.

20 The arm 42 includes a portion 46 which extends substantially parallel with the handle 41 and mounted in such a manner that as the handle 41 is held in the operator's hand, his thumb is placed on the free end of the portion 46 and pressed inwardly, causing pressure to be applied to the disc of the resistance 40, and the resistance of the same decreased 30 so that the current through the circuit formed by conductors 39 and the coil 37 may be increased. Releasing the handle 46 in a 35 reverse manner decreases the current.

35 It will be seen that the conductors 38, 39, the resistance 40 and the coil 37 form a closed circuit, and on account of the coil 37 being 40 placed in inductive relation with the coils 20 and 27, oscillating currents will be produced in said circuit.

45 The coil 37 is mounted in such a manner relative to the coils 20 and 27 that a portion 50 of the energy transferred from the plate coil 20 to the grid coil 27 will be consumed by the auxiliary circuit formed by the conductors 38, 39 and the coil 37, and thus providing means whereby the energy from the grid coil 55 to the output circuit may be controlled so that the current of the output circuit may be increased or decreased.

60 In actual construction all four inductance coils are mounted in a concentric manner, one within the other, in such manner that any one of said coils will be in inductive relation with all of the other coils.

65 Connected to the conductors 26 is a conductor 48 in which is included a variable condenser 49.

On account of the grid coil 27 being in inductive relation with the coil 20, the condenser 49 is made to tune the grid circuit and also control the frequency of the plate circuit, thus providing a single control for tuning 70 said circuits. The condenser 32 provides means for tuning the output circuit in resonance with the grid and plate circuits after the clamp 36 has been placed on the patient's wrist, and after the knife 33 has been placed 75 in operative relation on the body. Tuning of this circuit after the instruments have thus been placed is necessary, due to the fact that the capacity of the body of one patient is different from that of another patient. 80

In the drawing I have illustrated the filament and plate circuits with fixed voltages. These voltages may be varied if so desired, but I find under ordinary conditions that the variable condenser 49 provides ample means 85 for varying the frequency of the oscillator.

The operation of my circuit is substantially as follows: On account of the coils 20 and 27 being mounted in inductive relation, the energy from the battery 23 may be fed to the coil 20 and to the plates 18, and from the coil 20 to the coil 27 to cause the tubes to oscillate in the usual manner and in opposite phase, so that the amplitude of oscillations of the output circuit is thus increased from what would 90 be produced if a single oscillator were employed. This provides one means for producing extremely high efficiency of the circuit.

The condenser 49 is adjusted so that the tubes oscillate at the desired frequency, which 100 is determined by the action of the meter 24. The clamp 36 is then placed on the patient's wrist and the knife 33 applied to the body to form a closed output circuit. The condenser 32 is then adjusted and a reading taken from the meter 35, so that the plate circuit and the output circuit are in resonance. As before 105 described, it will be seen that energy will be absorbed by the auxiliary circuit, the amount of which is controlled through the variable resistance 40, and which, on account of absorbing a portion of the energy from the plate circuit will effect the amount of energy transferred to the coil 30 and to the output circuit. 110

115 Assuming that the filament and plate voltages are maintained constant, then it will be seen that a constant amount of energy is being delivered to the oscillating tubes, and consequently a constant amount of energy would be transferred to and divided between the coils 20 and 27, so that the sum of the currents of the auxiliary circuit and the output circuit is always equal to the total output of the oscillator.

120 It will, therefore, be seen that any variation of the current of the auxiliary circuit will vary the current of output circuit.

125 It will further be seen that inasmuch as the input and output energies are held constant, any tendency toward changing the frequency 130

of the oscillator, due to variation of the output currents, is eliminated, and inasmuch as all of the inductances and capacities of the circuits are maintained constant during a given operation, it will be seen that any desired frequency of the oscillator may be maintained throughout the entire operation, and at the same time the amount of the output circuit may be varied to suit the operator, to increase or decrease the cutting action of the knife. It should be understood that the actual cutting of the knife consists in a separation of the cells forming the tissues or muscles due to the electric influence on said cells, rather than by actually severing as with the ordinary surgical knife.

I claim as my invention:

1. In an electro-therapeutic apparatus the combination of an oscillatory circuit, a vacuum tube included in said circuit and comprising a grid and a plate circuit inductively coupled with each other, means for establishing in said circuit a variable predetermined high frequency oscillatory current, a variable capacity in said grid circuit for varying selectively the constants of said grid circuit, to thereby establish in the said oscillatory circuit an oscillatory current of predetermined frequency, a patient's circuit, means for inductively coupling said patient's circuit to said oscillatory circuit, means for varying the constants of said patient's circuit whereby it may be brought into resonance with said oscillatory circuit, and means for including an anatomical member in said patient's circuit.

2. In an electro-therapeutic apparatus the combination of an oscillatory circuit, a vacuum tube included in said circuit and comprising a grid and a plate circuit inductively coupled with each other, means for establishing in said circuit a variable predetermined high frequency oscillatory current, a variable capacity in said grid circuit for varying selectively the constants of said grid circuit, to thereby establish in the said oscillatory circuit an oscillatory current of predetermined frequency, a patient's circuit, means for inductively coupling said patient's circuit to said oscillatory circuit, means for varying the constants of said patient's circuit whereby it may be brought into resonance with said oscillatory circuit, means for including an anatomical member in said patient's circuit, an auxiliary absorbent circuit inductively coupled to the said grid circuit, and means for varying the amount of current in said auxiliary absorbent circuit for varying the amount of current in the patient's circuit.

3. In an electro-therapeutic apparatus the combination of two vacuum tubes, grid circuits for the tubes, inductances included in the grid circuits, plate circuits for the tubes, inductances included in the plate circuits, said inductances in the grid and plate circuits

being inductively coupled with each other in opposite phase, means for applying electrical energy to said circuits, a patient's circuit inductively coupled to the plate circuits, means for including an anatomical member in said patient's circuit, means for varying the constants of said patient's circuit, and means for varying the constants of said grid circuits whereby said grid and patient's circuits may be brought into resonance with each other.
